UNITED STATES PATENT OFFICE.

FRANK G. FAXON, OF MOUNT MORRIS, NEW YORK.

WATCH-CASE PENDANT.

SPECIFICATION forming part of Letters Patent No. 398,957, dated March 5, 1889.

Application filed October 9, 1888. Serial No. 237,650. (No model.)

To all whom it may concern:

Be it known that I, FRANK GEORGE FAXON, of Mount Morris, in the county of Livingston and State of New York, have invented a new and Improved Pendant-Set, of which the following is a specification, reference being had to the annexed drawings, forming a part thereof, in which—

Figure 1 is a vertical transverse section of a watch-pendant to which my improvement has been applied, showing the parts in position for drawing out the winding and setting stem, the section being taken on line $x-x$ in Fig. 4. Fig. 2 is a vertical transverse section, also taken on the line $x-x$ in Fig. 4, showing the winding and setting stem partly withdrawn from the pendant. Fig. 3 is an enlarged perspective view of the stem-holding springs. Fig. 4 is a transverse section taken on line $y-y$ in Fig. 1; and Fig. 5 is a sectional view of the watch-bow, showing the end received in the pendant.

Similar letters of reference indicate corresponding parts in all the views.

The object of my invention is to construct a pendant-set in which the watch-bow will retain the winding and setting stem within the pendant when in its normal position, but which will release the stem-holding springs when the

said bow is in a particular position.

My invention consists in the combination, with a pendant made in separable parts, of a bow having conical recessed ends received in bearings formed in the parts of the pendant and springs arranged to engage the winding and setting stem and adapted to be locked by the ends of the bow, all as hereinafter more fully described.

To the watch-rim A is fitted the pendant B, formed of four parts, the main portion a , screwed into the rim A, the sleeve b , screwed into the part a , the ring c , placed loosely on the sleeve b , and the nut d , screwed on the outer end of the sleeve b and clamping the ring c . The part a of the pendant is bored to receive the winding and setting stem C, and is provided with a shoulder, e , upon which rests the annular portion f of the double spring D. The annular portion f of the said spring supports the spring-arms g , which are provided at their free ends with heads h . The sleeve b is provided with longitudinal slots i in diametric-

ally-opposite sides for receiving the spring-arms g . The ring c , which is fitted to the outer end of the sleeve b , is preferably made 55 of the same diameter as the upper end of the part a , and in the upper surface of the ring is formed a conical recess, to which is fitted the conical nut d , which holds the ring in position upon the sleeve b . Both the nut and 60 sleeve are provided with nicks for receiving a screw-driver.

The bow E is provided with enlarged conical ends, which are received in the conical bearings j of the pendant B. The faces of 65 the adjoining ends of the bow E are parallel, and in the said faces are formed recesses k , of sufficient size to receive the ends of the heads h of the springs D when the said springs are thrown forward by the longitudinal movement of the winding and setting stem C. The stem C is reduced in diameter in two places, leaving the collar l , the said collar being provided with beveled faces to facilitate its passage between the ends of the double spring 70 75 D. The outer end of the winding and setting stem C is provided with the usual crown, F, and the inner end is squared for engagement with the winding and setting mechanism. The stem C is provided with the collar m for 80 limiting its outward movement.

The collar l of the stem C is engaged by the heads h of the spring-arms g , thereby preventing the drawing out of the said stem; but when the bow E is turned so as to cause 85 the recesses k in the ends of the bow to coincide in position with the heads h of the spring the stem C may be drawn out for the purpose of setting the watch, the beveled faces of the collar l pressing the arms g of the double 90 spring D outward, as shown in Fig. 2, the heads h being partly received in the recesses k .

My improvement prevents the accidental drawing out of the stem C and permits of the use of light springs for retaining the stem in 95 either of its positions, so that when the bow E is in a certain position the said stem may be readily drawn out or pushed in.

It is obvious that a single arm, g , of the spring D will serve to hold the stem C in 100 either of its positions, and that in such a case only one end of the bow E would need to be recessed. It is also obvious that by omitting the groove below the collar l the spring-arms

g will be compelled to remain in an expanded position so long as the said stem is pulled out. This will lock the bow E, so that it cannot be turned until the stem is returned to its normal position. This modification is important in hunting-case watches, in which case the bow is made to fold down over the bezel before the stem C can be pulled out, thus making it impossible to close the watch without first releasing the stem C and pushing it in. For this reason I do not limit or confine my invention to the exact form shown.

My improvement renders it possible to remove the winding-stem C from the pendant after taking out the sleeve b and spring D.

Having thus described my invention, I claim as new and desire to secure by Letters Patent—

1. In a pendant-set for watches, the combination, with the winding and setting stem, of one or more springs arranged to hold the stem in position for setting or winding the watch and a lock for holding the said spring or

springs in engagement with the winding and setting stem, substantially as specified. 25

2. In a pendant-set, the combination of the winding and setting stem C, provided with the collar l, the spring D, having the arms g, provided with heads h, and the bow E, having recesses k in the ends thereof, substantially as specified. 30

3. In a watch-pendant, the combination of the main part a, provided with the shoulder e, the ring c, the sleeve b, nut d, and the bow E, substantially as specified. 35

4. In a pendant-set, the combination of the part a, provided with the shoulder e, the slotted sleeve b, the ring c, nut d, the spring D, the bow E, having conical ends journaled in the part a and ring c and provided with recesses k, and the stem C, having the collar l, substantially as specified. 40
